ADJUSTABLE MAGNET

Joseph John Kehoe, Newark, N. J.

Application July 17, 1943, Serial No. 495,172

4 Claims. (Cl. 175—367)

This invention relates to an adjustable magnet and refers more particularly to a device for holding and withdrawing various metal objects and articles.

In factories and work shops small metal parts such as washers, bolts, nuts, etc., are often dropped by the workmen and fall into narrow holes and grooves; it is often difficult to locate and pick up these parts. Furthermore, it is sometimes necessary to remove metal washers from places behind various metal parts, which can not be reached by hand.

An object of the present invention is the provision of an adjustable magnet which is simple in construction and effective in operation, and which may be conveniently used for picking up and transporting various small metallic objects which may be attracted by the magnets.

Another object is the provision of a magnetic device for picking up various metallic articles, which is so constructed that the magnets may be conveniently adjusted, depending upon the size of the objects which are to be picked up, or the size of the recesses, grooves or holes wherein the articles are concealed.

Other objects of the present invention will become apparent in the course of the following specification.

In accomplishing the object of the present invention it was found desirable to provide a magnetic device comprising a preferably cylindrical handle portion, holding a magnet provided with downwardly extending curved prongs which may be located close to each other, or spread apart, depending upon the size of the objects to be transported. The magnet is preferably held in a clamping device which can be conveniently unscrewed for the purpose of adjusting the operative length of the prongs.

The invention will appear more clearly from the following detailed description when taken in connection with the accompanying drawing, showing, by way of example, a preferred embodiment of the inventive idea.

In the drawing:

Figure 1 shows in side elevation an article removing device constructed in accordance with the principles of the present invention.

Figure 2 is a bottom view of the device shown in Figure 3.

Figure 3 shows the same device from another side, with some parts broken off.

Figure 4 is a section along the line 4—4 of Figure 3, looking in the direction of the arrow.

The magnetic device, shown in the drawing, comprises a handle 17 which is substantially cylindrical in shape and which includes an inner chamber 18, containing a permanent magnet 19. The permanent magnet 19 extends beyond the handle 17 and is enclosed by a clamp 20, having the form of a metallic envelope provided with parallel flanges 21 and 22. The clamp 20 also encloses the upper ends of rods 23 and 24 which are bent at 25 and 26 respectively, and extend parallel to each other through the lower portion of their lengths.

The elongated prongs 23 and 24 are round in cross section, and are operatively connected with the permanent magnet 19, so that one of the prongs constitutes the south pole thereof. The prongs 23 and 24 fit into grooves or recesses provided in the permanent magnet 19.

The envelope 20 is firmly clamped over the permanent magnet 19, and the magnetic prongs 23 and 24, by means of bolts 27 and 28 which extend through the flanges 21 and 22, and which carry nuts 29 and 30 respectively.

If bolts, nuts, washers or other small metallic parts, have dropped into a comparatively shallow groove, or if they are to be removed from inaccessible recesses of a machine the user may hold the device by its handle 6 and introduce the prongs into the groove, or recess, for the purpose of picking up these small metallic articles which will become attracted by the magnetic prongs and will adhere to them. The same device may be conveniently used on comparatively flat but poorly illuminated floor surfaces for the purpose of picking up various small objects.

The user may conveniently adjust the operative distance between the prongs 23 and 24 extending below the clamp 20, merely by unscrewing the bolts 27 and 28 and thereby releasing the clamp 20. Then the user turns the prongs 23 and 24 to the desired position, whereupon the bolts 27 and 28 are screwed on again. This makes it possible to use the magnet for removing objects of various sizes. The prongs may be adjusted in the direction of the handle, thereby varying the length of the prongs projecting beyond the handle.

It is apparent that the illustration shown above has been given by way of illustration and not by way of limitation, and that the above described article is subject to wide variation and modification without departing from the scope or intent of the present invention. All of such variations and modifications are to be included within the scope of the present invention.

What is claimed is:

1. A magnetic device for picking up various objects, said device comprising a cylindrical handle having a hollow interior, a permanent magnet having a portion fitting firmly within the interior of said handle, a sleeve firmly enclosing another portion of said permanent magnet, and a pair of prongs having inner portions clamped between said sleeve and said permanent magnet, and outer projecting ends, said prongs operatively engaging said permanent magnet to constitute the poles thereof.

2. A magnetic device for picking up various objects, said device comprising a cylindrical handle having a hollow interior, a permanent magnet having a portion located within the interior of said handle, a sleeve, means carried by said sleeve for removably clamping the sleeve over another portion of said permanent magnet, and a pair of prongs having inner portions clamped between said sleeve and said permanent magnet, and outer projecting ends, said prongs operatively engaging said permanent magnet to constitute the poles thereof.

3. A magnetic device for picking up various objects, said device comprising a cylindrical han-

dle having a hollow interior, a permanent magnet having a portion located within the interior of said handle, a sleeve enclosing another portion of said permanent magnet, a pair of flanges upon said sleeve, screws upon said flanges for removably clamping said sleeve over said other portion of the permanent magnet, and a pair of prongs having inner portions clamped between said sleeve and said permanent magnet, and outer projecting ends, said prongs operatively engaging said permanent magnet to constitute the poles thereof.

4. A magnetic device for picking up various objects, said device comprising a handle having a hollow interior, a permanent magnet having a portion located within the interior of said handle, means firmly engaging another portion of said permanent magnet, and a pair of prongs having inner portions clamped between said means and said permanent magnet, outer projecting ends extending parallel to each other, and bent portions located between said inner portions and said outer ends, whereby the turning of said inner portions varies the operative distance between said outer ends.

JOSEPH JOHN KEHOE.
